To all whom it may concern.

Be it known that I, DE WANE B. SMITH, a citizen of the United States, and a resident of Deerfield, Oneida county, and State of New York, have invented and produced a new and original Design for a Body for Sprayers, of which the following is a specification, reference being had to the accompanying drawings, forming a part hereof.

5 Figure 1 is a side elevation of the design of body of sprayers. Fig. 2 is a perspective of the same.

10 The feature is the form and configuration of the article as shown in the drawings, con-

sisting of cylindrical portion 1 and dependent enlarged cylindrical portion 2, arranged at the end of portion 1 and at an angle, as shown.

20 The design for body of sprayers as herein shown and described.

In witness whereof I have hereunto affixed my signature this 8th day of July, 1898.
